Primary Examiner—Wallace R. Burke*Assistant Examiner*—Marcus Jackson*Attorney, Agent, or Firm*—Cushman, Darby & Cushman[57] **CLAIM**

The ornamental design for a sign holder, as shown and described.

DESCRIPTION

FIG. 1 is a front plan view of a sign holder showing my new design;

FIG. 2 is a rear plan view thereof;

FIG. 3 is a right side elevational view thereof, the left side elevational view being a mirror image thereof;

FIG. 4 is a sectional view taken along line 4—4 of FIG. 1;

FIG. 5 is a bottom elevational view thereof;

FIG. 6 is a top elevational view thereof;

FIG. 7 is a sectional view taken along line 7—7 of FIG. 1; and,

FIG. 8 is a top, front prospective view of a sign holder showing my new design.

FIG. 1
